(57) **CLAIM**

The ornamental design for antenna housing, as shown and described.

DESCRIPTION

FIG. 1 is a bottom perspective view of an antenna housing; FIG. 2 is a top perspective view of the antenna housing in FIG. 1;

FIG. 3 is a top view of the antenna housing in FIG. 1; FIG. 4 is a bottom view of the antenna housing in FIG. 1; FIG. 5 is a front view of the antenna housing in FIG. 1; FIG. 6 is a rear view of the antenna housing in FIG. 1; FIG. 7 is a left view of the antenna housing in FIG. 1; and, FIG. 8 is a right view of the antenna housing in FIG. 1.

Throughout the figures, the thin parallel lines on surfaces of the antenna housing represent only shading and do not illustrate ornamentation or decoration.

The broken lines illustrate portions of the article, and form no part of the claimed design.
